UNITED STATES PATENT OFFICE

WILLIAM M. SHEEHAN, OF ST. LOUIS, MISSOURI, ASSIGNOR, BY MESNE ASSIGNMENTS, TO GENERAL STEEL CASTINGS CORPORATION, OF GRANITE CITY, ILLINOIS, A CORPORATION OF DELAWARE

PILOT BEAM

Application filed March 10, 1928. Serial No. 260,792.

My invention relates to railway rolling stock and consists in a novel construction of the transverse end member of a railway vehicle framing adapted to mount the uncoupling lever or levers which are in general use.

It has been the practice heretofore to provide a plurality of brackets, formed separately from the framing member, and to assemble the same with the framing by bolting, riveting or other means. This construction involves a substantial amount of fitting, drilling or other machining when the brackets are applied to the frame member and, due to the exposed position of the brackets and the levers mounted thereon, the securing elements frequently loosen so that the brackets are not rigid and may even become detached from their base and, in either case, fail to function properly in journaling the uncoupling levers.

The object of my invention is to eliminate these disadvantages, and I attain this object by forming the brackets integrally with the framing member, thereby eliminating all machining necessary for assembling the two parts and also eliminating the likelihood of the uncoupling lever journals in the brackets being disaligned or the likelihood of the uncoupling lever dropping because of the failure of one or more of its brackets or the bracket holding elements.

In the accompanying drawings which illustrate a selected embodiment of my invention,—

Figure 1 is a front elevation of a locomotive pilot beam provided with integral uncoupling lever brackets.

Figure 2 is a top view of the same.

Figure 3 is an end view of the same and is drawn on an enlarged scale.

Figure 4 is a vertical transverse section taken on line 4—4 of Figure 1 and drawn on an enlarged scale.

The pilot beam illustrated is of a general box section having a front wall 1, rear wall 2, top wall 3, a lower wall 4, and an intermediate horizontal web 5 which forms the lower wall of the beam at the ends thereof which are of less depth than the central portion,

Preferably the beam is formed of a one-piece casting and near each end of the same I provide a bracket comprising an upward and outward extension 6 of the front wall 1 and suitable reinforcing ribs 7, the same merging at the upper end to form two ears 8 providing a bearing 9 between them in which the outer end of the uncoupling lever 10 may be journaled.

Near the center of the beam I provide a central bracket including a forwardly facing web 11, extending upwardly and outwardly from the front wall of the beam, and terminating in a rearwardly extending flange 11a. The same is reinforced by suitable ribs 12. This bracket is somewhat wider than the end brackets and is provided with spaced ears 13 and 14, each pair of ears providing a bearing 15 for the inner end of one of the uncoupling levers 10. This bracket may be perforated as indicated at 16 to lighten the casting and preferably a reinforcing rib 17 will surround the opening 16.

While I have illustrated my invention as embodied in the pilot beam of a locomotive, it will be understood that the brackets may be formed integrally with the end sill of a car where they will function the same as on a pilot beam.

While I have shown a bracket on each end of the pilot beam and a bracket with a double bearing at the center of the pilot beam, in order to mount two uncoupling levers, it will be understood that brackets may be provided for a single uncoupling lever if desired.

Various other modifications in the details of the structure may be made without departing from the spirit of my invention, and I contemplate the exclusive use of such modifications as come within the scope of my claims.

I claim:

1. A railway vehicle framing transverse end member having an uncoupling lever bracket formed integrally therewith.
2. A one-piece casting comprising a railway vehicle framing transverse end member and including a bracket for mounting an uncoupling lever.
3. A one-piece casting comprising a railway vehicle framing transverse member hav-

ing a box-shape body cross section and including a bracket extending upwardly from the top wall of said body and forwardly of the front wall of said body.

5 4. In a railway vehicle framing transverse end member, brackets integrally with said member and located intermediate the ends thereof and near an end thereof respectively, said brackets having aligned bearings for 10 journaling an uncoupling lever.

5. In a railway vehicle framing transverse end member, side brackets formed integrally with said member and located near the ends thereof and provided with uncoupling lever 15 bearings, and a center bracket formed integrally with said member and located intermediate the ends thereof and having a plurality of uncoupling lever bearings, each aligned with the bearing in one of said side 20 brackets.

25 6. A one-piece casting forming a box-shaped end member for a railway vehicle framing and including a box-shaped body and integral brackets extending upwardly and outwardly from the top front edge of 30 said body, located near the center and at each end of said body, respectively, and provided with bearings for journaling uncoupling levers extending from the center of said member to each side thereof and operating independently of each other.

7. A locomotive pilot beam with an uncoupling lever bracket formed integrally therewith.

35 8. A one-piece casting comprising a locomotive pilot beam including a plurality of uncoupling lever brackets extending upwardly therefrom.

40 9. A one-piece casting comprising a locomotive pilot beam having a body of box-shape cross section, a portion of the front wall of which extends upwardly to form an uncoupling lever bracket.

45 In testimony whereof I hereunto affix my signature this 28th day of February, 1928.
WILLIAM M. SHEEHAN.
